UNITED STATES PATENT OFFICE

2,135,402

REFRIGERATOR

Eugene Korber, Windsor, Ontario, Canada

Application July 31, 1935, Serial No. 34,094

1 Claim. (Cl. 62—99)

This invention relates to improvements in a refrigerator. The primary object of the invention is to provide means to carry a standard refrigerant in close proximity to a refrigerator wall 5 as manufactured in a standard domestic refrigerator, or the well or chamber of an ice cream cabinet refrigerator.

A further object of the invention is to provide improved means for circulating the refrigerant medium. Heretofore, it has been common practice to carry the same in copper pipes or tubing, which has been found, by those skilled in the art to be unsatisfactory due to the nature and ingredients of the said refrigerant, the pipes or tubing 10 being constantly in need of repair as the solder is eaten away thereby.

A still further object of the invention is to replace the said coils by a double sleeve device carrying the refrigerant medium therebetween 15 and having means in conjunction therewith whereby two or more of the said sleeves may be connected together for any desired purpose, one of which being the multiple well ice cream cabinet shown in the drawings.

With these and other objects in view that may appear from the description, the invention consists in the novel construction and arrangement of parts as hereinafter more specifically set forth, claimed and shown in the accompanying drawings forming part of this application and in which:

Fig. 1 is a sectional view of a multiple well ice cream refrigerator cabinet showing my invention installed therein.

Fig. 2 is an enlarged detail sectional view of the upper end of the sleeves showing the connecting means.

Fig. 3 is a plan view of Fig. 1.

Fig. 4 is a sectional view on the line 4—4 of Fig. 1, showing modified construction of various shapes of the refrigerant chambers.

Fig. 5 is a vertical sectional detail view of the sleeves showing the construction thereof.

Referring more in detail to the drawings in which similar reference characters designate corresponding parts throughout the several views it will be seen the invention comprises an insulated cabinet 10 constructed of standard lines and containing therein one or more chambers or wells 11 to receive the standard ice cream container. Surrounding the wells is an inner wall 12 which constitutes the wall of the said well. This wall may be cylindrical as shown or may be square in cross-section or any shape to suit the purpose for which it is required as shown in Fig. 4, and ex-

tends from the bottom of the well to within a convenient distance from the top. An outer wall 13 is arranged to fit outside the inner wall 12 leaving a space 14 therebetween. This outer wall 13 may be of any required length and has a flange 15 formed on the top and a similar flange 16 on the bottom thereof. The said flanges extend 5 inwards toward the inner sleeve to which they are joined preferably by welding. As shown in Fig. 5, the said sleeve 13 may be of any desired 10 length according to the amount of refrigerant it is required to carry. Obviously the longer the sleeve the greater will be the capacity of the refrigerant space 14 and consequently the effect 15 on the contents of the well will be greater.

Where more than one such well is to be used, as in the case of the multiple well ice cream cabinet shown, the outer walls are provided with couplings 16 and 17, which are preferably welded thereto. The said couplings are arranged either 20 diametrically opposite or at right angles to each other so that the same may be connected together in any convenient manner. The couplings may be threaded for screwing together as shown or may be joined by a union fitting or if so desired 25 they may be telescoped and welded together for a more permanent connection.

In Fig. 4 is shown a variety of different shaped chambers 11 to which the construction may be adapted. The outer and inner walls of the chambers being formed from one or a number of plates welded together with top and bottom flanges between the walls and welded thereto retain the walls in spaced apart relation to each other and form closure means whereby the refrigerant medium is retained between the walls.

The condenser unit 18, condenser coil 19 and float device 20 are all of standard manufacture as used in refrigerating apparatus now on the market. These units are connected to the sleeves 40 by an intake pipe 21 and an outlet pipe 22 positioned above the same. The pipes are screwed into a cover 23 on the end of the coupling 16. While they are both shown at the same end of the cabinet this arrangement may be changed and one shown at one end and one at the opposite end of the cabinet, but in either instance it will 45 of course be necessary to keep the inlet and outlet in their relative elevation with respect to each other.

In operation the space between the walls is filled with the refrigerant medium to a height midway between the inlet and outlet pipes. The said refrigerant being in close proximity to the contents of the well reduces the temperature 55

thereof very rapidly which causes an evaporation of the liquid. The vapor thus formed is drawn through the outlet or suction pipe, through the compressor to the condenser and circulates back through the float chamber to the sleeves again in its liquid form.

It is believed that the construction and advantages of the structure shown may be apparent from the foregoing paragraphs taken in conjunction with the accompanying drawings without further detailed description.

While the preferred embodiment of the invention has been disclosed, it is understood that minor changes in the details of construction, combination and arrangement of co-operating elements may be resorted to within the scope of what is claimed without departing from the spirit of the invention.

I claim:

A refrigerating unit comprising an insulated cabinet having a series of chambers therein arranged in spaced parallel relation, a double wall cylindrical metal lining extending entirely around the wall of each chamber, the walls of said lining being spaced apart with the inner wall extending the full length of the chamber and the outer wall extending only part the length of the inner wall and connected at the top and bottom to the inner wall forming a refrigerant circulating space and sleeves extending from the outer walls of said lining at diametrically opposite points, the sleeves of each lining being adapted to telescopically interfit with the sleeves of the lining in the next adjacent chambers and welded together to establish communication between the refrigerant space of each of the linings. 5 10 15
